UNITED STATES PATENT OFFICE.

JOHN J. HEYS, OF LYNN, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

1,341,746.

Specification of Letters Patent. Patented June 1, 1920.

Application filed August 26, 1918. Serial No. 251,437.

To all whom it may concern:

Be it known that I, JOHN J. HEYS, a citizen of the United States, residing at Lynn, in the county of Essex and State of Massachusetts, have invented certain Improvements in Methods of Making Shoes, of which the following description, in connection with the accompanying drawings, is a specification, like reference characters 10 on the drawings indicating like parts in the several figures.

The present invention relates to improved methods of manufacturing shoes and it is herein illustrated in connection 15 with the manufacture of shoes of the type known as "turn" shoes.

The invention has for its object to provide an improved method of making shoes and especially turn shoes, the practice of 20 which will enable the sole of the shoe to be given any desired sole contour independently of the shape of the last upon which the shoe upper is shaped and without disturbing the shape imparted to the upper 25 or interfering with the usual steps performed in making the shoe.

With this object in view the invention, in one of its aspects, consists in conforming a shoe upper to the shape of the last selected for the purpose, the shoe upper being 30 stretched and conformed to the contour of the selected lasting last and caused to retain that shape by any of the usual or suitable pulling-over, lasting and shaping methods, including the first lasting and the 35 sewing of the shoe while inside out and then turning the shoe right side out and relasting the shoe; and in then imparting the desired shape to the sole of the shoe independently of the last upon which the shoe 40 upper was shaped by applying a direct molding pressure over substantially the entire shoe bottom simultaneously.

This method has the great advantage that 45 various shapes of shoe bottoms can be obtained in shoes made on a single style of lasting last. Thus a manufacturer can change in a conspicuous respect the style of his shoe from one season to another, or 50 for sale in different parts of the country, by changing his molds but without incurring the expense of buying new lasts. For example, the last employed may have, together with a contour giving a pleasing appearance to the shoe upper, a bottom face

of continuous lines. In the sole shaping step of this method the bottom of the shoe may be given a shape in which there is a sharp "break" or well-defined line across the ball, or it may be given in the shank the 60 shape known as a "cottage shank." Any shape may be obtained quite independently of the contour or shape of the bottom face of the last.

The bottom shaping operation is preferably practised with the aid of a metallic member applied within the shoe, the second last being withdrawn, and a metallic form which is made to engage the outside of the sole with heavy direct pressure effecting a 65 molding of the entire shoe bottom simultaneously. It is important that the bottom shaping operation be performed while the sole is thoroughly in temper, the right condition being usually found to exist directly 70 after the second lasting and before the shoe has been allowed to "set" or dry. In an advantageous system the heel is also attached while the second last is withdrawn, after which a "filler" last is inserted over which 75 the shoe is allowed to "set" during a day and which prevents distortion of the shoe upper by handling during the sole edge and heel trimming and other finishing operations.

In shaping the shoe bottom, a "filler piece" of desired shape may be used to cooperate with the forms in imparting the desired shape to the sole in the shank and at the "break" in the ball, such filler pieces 80 usually also serving the purpose of presenting an even surface for the wearer's foot. The filler piece is applied before the forming, and usually before the second lasting, and remains permanently in the shoe, 85 the sole being molded over it.

The invention will be better understood from the following description and the accompanying drawings which disclose one way in which this method has been successfully practised, and the invention will be definitely pointed out in the claims.

Figure 1 of the drawings shows a turn shoe upon which has been performed, in the usual or in any well-known manner, the 105 steps of shaping the upper to a last having the contour which it is desired to reproduce in the upper of a completed shoe, sewing the upper to the sole, withdrawing the last, turning the shoe, second lasting the shoe, 110

inserting a filler piece extending from the heel seat forwardly through the shank and to the "break" at the ball, lasting the heel seat over said filler piece, and nailing the 5 heel seat of the sole;

Fig. 2 is a transverse section through the shoe of Fig. 1, the last being withdrawn;

Fig. 3 is a perspective view of the last over which the shoe upper was shaped;

10 Fig. 4 is a sectional view through the sole conforming members and a shoe to illustrate the relation of the members and the shoe prior to the application of pressure to the sole;

15 Fig. 5 shows the operation of effecting by direct pressure applied substantially simultaneously over the entire shoe bottom, by means of inner and outer forming members, the shape or contour which is desired 20 in the bottom of the completed shoe, such shape or contour differing from the contour of the bottom face of the last over which the upper was shaped;

25 Fig. 6 is a perspective view showing the operative surfaces of the forms by which the shoe bottom was shaped;

30 Fig. 7 shows the shoe made in accordance with this invention by shaping the upper into conformity with faces of the lasting last and shaping the shoe bottom by direct pressure into conformity with forms having a contour materially differing from the contour of the bottom face of said last.

35 In the practice of this invention as it has been successfully carried out, a turn shoe is made by assembling a sole 2 and upper materials 4 on a last 5 having a contour which it is desired to reproduce in the upper 4 of the completed shoe. The upper materials 4 are assembled wrong side out upon the last 5, and they are pulled over and lasted in the usual manner and sewed to the sole 2. The 40 sewing may be extended entirely around the shoe to produce the "sewed seat" type of shoe. In the drawings, is shown a shoe of the nailed seat type in which the sewing is 45 terminated at the heel seat and after the shoe is turned right side out and second lasted and the heel seat piece 10 inserted in the shoe, the heel seat portion of the upper 4 is lasted over the heel seat piece and fastened by tacks, the heel end portion of the sole being thereafter laid down over the lasted heel seat and nailed in place by nails 50 11. These steps are well known in the art and it is therefore unnecessary to describe them in greater detail.

55 After the completion of the work associated with second lasting the shoe which includes lasting the heel seat and nailing the sole, if it is a nailed seat shoe as shown, the last 5 is withdrawn while the shoe sole is still in good temper. This it has been found, may be done immediately after the 60 above-described operations are completed

and then the shoe is applied to a sole shaping member 12 which is preferably the full length and width of the shoe and has a surface contour 13 corresponding with that which it is desired to reproduce on the inside or foot-engaging surface of the shoe bottom. This member may be advantageously adapted for mounting upon the pressure spindle of a direct pressure sole leveling machine such, for example, as that 70 shown in United States Letters Patent No. 1,280,875, granted October 8, 1918, on application of Thomas H. Seely, and owned by the assignee of the present invention. The outer or tread face of the shoe bottom is 80 then engaged by a shaping member or form 15 having an operative face 16 corresponding with the contour or shape which it is desired to produce in the bottom of the finished shoe. This shaping member 15 85 may conveniently be a surface form adapted to form an operative element of said sole leveling machine as illustrated in Fig. 5. The operative or sole shaping faces 13, 16 of the members 12 and 15 respectively may 90 be materially different and need have no particular relation to the contour of the bottom face of the last over which the upper shaping operations are performed. It will be understood that the bottom shaping operation as performed in accordance with this invention is not dependent upon the shape of the bottom face of the last 5, for example, upon which the shoe upper was 95 shaped and the contour or shape produced 100 in the tread face of the shoe bottom may differ very radically from the contour of the bottom of this last. In fact by varying the shaping members 12 and 15, various 105 styles of shoes may be produced on the same first last in the sense that the shoe bottoms will differ radically from one another. For example, the shaping members 12 and 15 illustrated are adapted to produce a shoe 110 bottom having the diverging break lines 21 and 22 (see Fig. 6) prominently appearing between the ball and shank of the shoe and to produce the prominent peak line 23 extending longitudinally of the shank. This 115 is one popular style of shoe bottom. Obviously the surfaces of the bottom shaping members 12, 15 may be modified to produce a break extending in a single line across the shoe bottom, or in a curved line, and to produce a rounded instead of a peaked shank. 120 From the foregoing it will be readily understood that this invention has the advantage of enabling a manufacturer to produce a plurality of styles of shoes upon the same lasts, the expense for replacing one pair of iron lasts and forms with another being insignificant as compared with the expense of replacing one set of lasts by a last equipment having a different bottom contour.

125 The shoe having been mounted upon the 130

shaping member 12 is presented to the shaping member 15 and pressure applied in a direction substantially perpendicular to the shoe bottom over the entire surface of the 5 shoe bottom simultaneously. The sole shaping operation is performed while the sole is in temper, which is directly after the second lasting, and responds readily to the shaping action of the members 12 and 15. The pressure 10 is of such extent and is maintained such time as is necessary to render permanent the shape being imparted to the shoe bottom. Thereafter the members 12, 15 are separated and the shoe removed.

15 The last 5, or it may be a filler last which will more easily slip into the shoe, is inserted after the bottom shaping operation, and the shoe is preferably then allowed to stand on the last for the shoe materials to 20 set or assume the permanence of shape that has been imparted to them. Usually turn shoes are allowed to set on the last for at least one day, after which the edge trimming and other finishing operations are performed while the last is retained in the shoe 25 to prevent misshaping of the upper occurring from handling of the shoe. The heel may be attached to the shoe directly after the bottom shaping operation and while the 30 shoe is off the last, or the heel attaching operation may be deferred until after the shoe has set. Some of the advantages of this invention may be obtained when the bottom shaping operation is effected by a 35 direct pressure mold, such as the mold 15, while the last is in the shoe. In that case the last takes the place of the shaping member 12. I prefer, however, to employ the shaping member 12 because it can be made 40 stronger than is a last, thereby permitting the application of more effective molding pressure.

Another important advantage for employing the forming members 15, 12 for shaping the shoe bottom is that these members can 45 be so shaped and so operated as to produce a uniform molding pressure, whereas lasts differ from one another slightly more or less and also change shape and volume with 50 changes in atmospheric conditions, thus rendering uniformity of product difficult, if not impossible, to obtain. Also a greater range of variation in bottom contour is obtainable in the finished shoe if the last is 55 not depended upon as one of the bottom shaping members.

60 Preferably the acting surfaces of the iron last and form 12 and 15, respectively, may be such as to effect a more pronounced longitudinal and transverse curvature than exists in the sole face of the lasting last over which the shoe upper was shaped or than is finally desired in order to compensate, after the shaping operation has been performed 65 on the sole, for the reaction and drawing

out of the sole after pressure of the form is released.

Having explained the nature of this invention and described how it may be employed, I claim as new and desire to secure 70 by Letters Patent of the United States:—

1. That improvement in methods of making turn shoes which consists in conforming the upper to the shape of a last which has the contour that it is desired to reproduce 75 in the upper of the shoe, said operations including sewing the upper to the sole inside out, turning the shoe, and relasting the shoe, and thereafter withdrawing the second last and shaping the shoe bottom by direct pressure applied over substantially the entire shoe bottom simultaneously. 80

2. That improvement in methods of making turn shoes which consists in conforming the upper to the shape of a last which has 85 the contour that it is desired to reproduce in the upper of the shoe, said operations including lasting and sewing the shoe upper to the sole while the shoe upper is inside out, turning the shoe and relasting the shoe and 90 thereafter placing the sole of the shoe between the inner and outer molding members and applying a direct pressure to all parts of the shoe bottom substantially simultaneously to impart the desired shape to the bottom of the shoe. 95

3. That improvement in methods of making turn shoes which consists in shaping the upper over a last having upper shaping faces which it is desired to reproduce in the 100 upper of a finished shoe and having a sole face differing from the shape which it is desired to reproduce in the completed shoe; withdrawing the last from the upper after the upper shaping operations have been 105 effected; introducing into the shoe a sole-shaped form presenting a sole face differing in contour from the sole face of the last; and shaping the shoe bottom between said member and a coöperating mold or form having 110 a sole engaging face representing the contour desired to be reproduced on the bottom face of the shoe.

4. That improvement in methods of making turn shoes which consists in shaping the 115 upper over a last having upper shaping faces which it is desired to reproduce in the upper of a finished shoe and having a sole face differing from the shape which it is desired to produce on the outside of the finished shoe; withdrawing the last; incorporating in the shoe a filler piece; and then effecting, by direct pressure applied over substantially the entire shoe bottom simultaneously, a forming of the shoe bottom into a 120 shape differing substantially from the sole face of the last. 125

5. That improvement in methods of making turn shoes which consists in first lasting an upper over a last having a contour which 130

it is desired to reproduce in the upper of a finished shoe, sewing the upper to the sole, withdrawing the last, turning the shoe, second lasting the shoe, withdrawing the last 5 before the sole dries, shaping the entire outer surface of the sole by direct pressure to produce the shoe bottom contour desired in the finished shoe, heelng the shoe, inserting a last or filler, maintaining the shoe 10 on said last or filler while the upper sets, edge trimming and otherwise finishing the shoe and thereafter withdrawing the last.

6. That improvement in methods of making turn shoes which consists in first lasting 15 an upper over a last having a contour which it is desired to reproduce in the upper of a finished shoe, sewing the upper to the sole, withdrawing the last, turning the shoe, second lasting the shoe, withdrawing the last 20 before the sole dries, leveling the entire sole by direct pressure to produce the shoe bottom contour desired in the finished shoe, inserting a last or filler, maintaining the shoe on said last or filler while the upper sets, 25 completing the shoe, and then withdrawing the last.

7. That improvement in methods of making turn shoes which consists in conforming the upper to the shape of a last which 30 has the contour that it is desired to reproduce in the upper of the shoe, said operations including sewing the upper to the sole inside out, turning the shoe, and relasting the shoe; and thereafter withdrawing the 35 second last and overmolding the shoe bot-

tom by direct pressure applied over substantially the entire shoe bottom simultaneously and effecting more pronounced longitudinal and transverse curvatures in the sole than exist in the sole face of the last 40 over which the shoe upper was shaped.

8. That improvement in methods of making turn shoes which consists in conforming the upper to the shape of a last which has the contour that it is desired to reproduce 45 in the upper of the shoe, said operations including lasting and sewing the shoe upper to the sole while the shoe upper is inside out, turning the shoe and relasting the shoe, and thereafter imparting the desired shape 50 to the bottom of the shoe independently of the lasting last by subjecting the sole of the shoe to a direct pressure applied to all parts of the shoe bottom substantially simultaneously between inner and outer metal forms. 55

9. That improvement in methods of making turn shoes which comprises making the shoe wrong side out on a last, turning the shoe right side out, second lasting the shoe, including the application of the filler to the 60 inner side of the sole and, while the sole of the shoe is in temper, placing the sole upon a metal last and then subjecting the outer surface of the sole to a direct pressure by a form coöperating with the said metal last 65 and filler and having a sole faced surface contour of the desired conformation.

In testimony whereof I have signed my name to this specification.

JOHN J. HEYS.
